(Cl. D92—1)

The figure is a top plan view of a textile fabric, showing my new design.

The characteristic features of my design reside in a plurality of parallel stripes consisting of braid-like stitches in raised relation to the crinkled base fabric, forming alternate bands of braid-like stitches and crinkled fabric, the crinkles being for the most part horizontally disposed and perpendicular to the vertical parallel stripes of the braid-like stitches as shown.

I claim:

The ornamental design for a textile fabric or similar article, substantially as shown and described.
